BOILER CONSTRUCTION

James F. McIntire, Detroit, Mich., assignor to
United States Radiator Corporation, Detroit,
Mich., a corporation of New York

Application May 1, 1933, Serial No. 668,878

14 Claims. (Cl. 122—218)

This invention relates generally to boiler constructions and consists of certain novel features of construction, combinations and arrangements of parts that will be hereinafter more fully described and particularly pointed out in the appended claims.

In the accompanying drawings:

Figure 1 is a front elevation of a boiler embodying my invention with parts broken away and in section;

Figure 2 is a sectional view on the line 2—2 of Figure 1 with the outer jacket or casing removed;

Figure 3 is a sectional view on the line 3—3 of Figure 2;

Figure 4 is a detail bottom plan view of the lower flue section;

Figure 5 is a detail bottom plan view of the intermediate flue section;

Figure 6 is a sectional view on the line 6—6 of Figure 5;

Figure 7 is a detail bottom plan view of the upper flue section.

Referring now to the drawings, A is the base; B is the fire pot; C, D and E, respectively, are the flue sections; F is the insulation; and G is the jacket or outer casing of a boiler embodying my invention. As shown, the base A, fire pot B, insulation F and jacket G are conventional in construction and design and are assembled in the usual manner. The sections C, D and E, respectively, however, are structurally quite different from any of which I have knowledge and constitute the subject matter of my invention.

Preferably the lower section C is a hollow casting having an arched bottom 1 and a substantially flat top 2. As shown, the arch 1 extends fore and aft of the section and is open at the front and closed at the rear. The section C is also provided in a line extending at substantially right angles to the fore and aft line of the arch with an elongated vertical opening 3 and the usual circular bosses 4 and 5, respectively. Two sets 6 and 7, respectively, of parallel fins extend

45 downwardly from the ceiling of said arched portion in front and in rear of the elongated opening 3 and extend fore and aft of the section. Preferably the fins of the front set 6 extend from points adjacent the forward open end of the 50 arched portion 1 to the front edge of the opening 3 while the fins of the rear set 7 are in alignment with the fins of the front set and extend from the rear edge of the opening 3 to the closed rear end of the arched portion.

55 The intermediate section D is also a hollow

casting having an arched bottom 8 and a substantially flat top 9. As shown, the arch 8 extends fore and aft of the section and is open at the front and closed at the rear. The section D also is provided at diametrically opposite points 5 thereof in a line extending substantially at right angles to the fore and aft line of the arch with the usual circular bosses 10 and 11. In the present instance, however, the section D is provided with two sets 12 and 13, respectively, of vertical 10 openings and only one set 14 of depending fins. As shown, the openings of the set 12 are spaced laterally apart in the arc of a circle at the forward end of the arch 8 while the openings of the set 13 are spaced laterally apart in the arc 15 of a circle at the rear end of the arch. Preferably the left hand opening of the front set 12 is in alignment with the left hand opening of the rear set 13 and the right hand opening of the front set 12 is in alignment with the right hand 20 opening of the rear set 13. The fins of the single set 14 are parallel and extend fore and aft of the section between the sets 12 and 13 of openings.

The upper or dome section E is also a hollow 25 casting and is provided with an arched bottom 15. As shown, this arch extends fore and aft of the section and is open at the front and closed at the rear. The section E is also provided at diametrically opposite points thereof in a line extending substantially at right angles to the fore and aft line of the arch with the usual circular bosses 16 and 17 and is provided at the center thereof with a vertical opening 18 of circular configuration. Preferably an open ended fluidway 19 of substantially 30 rectangular configuration extends diametrically across this opening 18 at the lower end thereof.

In the present instance, the usual upstanding smoke hood or flue pipe is dispensed with entirely and the gases or products of combustion flowing 40 upwardly in the opening 18 upon opposite sides of the fluidway 19 are directed horizontally within the dome section E itself to a laterally projecting smoke pipe such as 20. As shown, the dome section E is provided at one side of the 45 opening 18, preferably above and in vertical alignment with the fluidway 19, with a channel-shaped portion 18' that constitutes a lateral extension of the opening 18 to the flue 20. The bottom 50 18' of this channel portion is flush with the top of the fluidway 19 while the upper edges of the channel portion are flush with the upper end of the opening 18. Thus, the channel portion 18' is above the water level in the boiler and ample 55 liberating surface for steam is provided. Prefer-

ably a casting H is secured upon the dome E and has a flat portion 19' and a tubular portion 20'. The flat portion 19' serves as a cover for the channel portion 18' and has a suitable clean-out opening 19² provided with a hinged lid 19³, while the tubular portion 20' is in line and cooperates with the trough-shaped portion 18' to conduct the gases to the pipe 20. A reduced part 20² of the tubular portion 20' constitutes an attaching portion for the pipe 20. Any suitable means such as the bolts 18³ may be used as the securing means for the casting H and any suitable means such as putty 20³ held by the portions of the casting may be used to effect a proper seal between the parts.

15 Two sets 21 and 22, respectively, of parallel fins extend downwardly from the ceiling of the arched portion 15 in front and in rear of the opening 18 and extend fore and aft of the section. Preferably the fins of the front set 21 extend from 20 points adjacent the forward end of the arched portion 15 to the forward edge of the opening 18, while the fins of the rear set 22 are in alignment with the fins of the front set and extend from the rear edge of the opening 18 to the closed rear end 25 of the arched portion 15. In this instance, the vertically extending parallel fins 23, 24, 25 and 26, respectively, are provided upon opposite sides of the fluidway 19 and upon opposite walls of the opening 18. Preferably the fins 23 and 24 are 30 staggered with respect to the fins 25 and 26 and are equal in height to the height of the fluidway 19.

Upon installation the sections C, D and E are arranged in superposed relation upon the fire pot B and are bolted together as illustrated in 35 Figure 1. Preferably a door J is hingedly mounted upon the fire pot B to close the open forward ends of the arched portion 1 while a door K is hingedly mounted upon the sections C and D to close the 40 open forward ends of the arched portions 8 and 15. Any suitable means such as the push nipples 27 accurately machined and gauged may be used in the bosses 4, 5, 10, 11, 16 and 17 to establish the proper fluid connections between the 45 sections and the fire pot B.

In use, water will circulate in the hollow portions 30, 31, 32 and 33, respectively, of the fire pot B and sections C, D and E and through the nipples 27 and fluidway 19 and will be heated by 50 the products of combustion or gases passing upwardly from the fire pot B to the flue 20. In this connection it will be noted that the gases flowing upwardly from the fire pot B will be initially divided by the two sets 6 and 7 of overhanging fins into a number of small streams which will flow longitudinally of said fins into the opening 3 where they will be thoroughly commingled. Such gases will then flow upwardly against and be divided by the overhanging set 14 of fins into 55 streams which will flow longitudinally thereof to the two sets 12 and 13 of openings where they will be commingled. Upon being discharged from these openings the gases will again be divided by the two sets 21 and 22 of overhanging fins into streams which will be received and commingled 60 in the opening 18. The fluidway 19 will cause a further division of the gases before they enter the flue 20. Thus the gases are successively divided and commingled in their passage upwardly from the fire pot B to the flue 20 and the heated particles thereof are thoroughly broken up and absorbed. Inasmuch as the opening 3 is elongated and is centrally located in the section C the commingled gases will be substantially uniformly distributed beneath the set 14 of fins de-

pending from the intermediate section D. The sets 6, 7, 14, 21 and 22, respectively, of horizontal fins and the vertical fins 23, 24, 25 and 26, respectively, not only play a major part in the breaking up of the gases but also add materially to the heat absorbing means of the boiler. They are deep enough to compel the greater part of the gases to pass between them. Moreover, they are so arranged that the stratification of gases is effectively broken up. The hottest gases move by natural convection in the spaces between the fins. In fact, the construction is such that added heating means is provided in a limited space. The fins serve as guides instead of baffles. In this connection it will be noted that such fins extend 10 in the direction of travel of the gases and two passages instead of one are provided for the gases, hence the flow upwardly is continuous and draft loss is not materially increased. It will also be noted that the sets 6, 7, 14, 21 and 22, respectively, of horizontal fins are in line with the open forward ends of the arched portions 1, 8 and 15 and are therefore accessible when the doors J and K are opened, hence they may be readily cleaned whenever desired. However, in practice, the necessity for manually cleaning such fins is minimized since the gases in effect automatically cleanse said fins as they flow longitudinally thereof in their passage upwardly to the flue 20. The casting H serves as a cover for the channel-shaped portion 18' while the tubular portion 20' serves as an extension of said portion 18' to the pipe 20. Thus the casting H cooperates with the dome E to form a passageway within the boiler for the products of combustion or gases; the over-all height of the boiler is less; the length of the gas passageway in the boiler is increased and an additional turn in the gas passageway operable to break up the gases is provided. As a result the gases pass over a greater area of the boiler and the heat absorption is accordingly increased. In all, a more efficient and reliable boiler construction is provided.

What I claim as my invention is:

1. A boiler having a base, a fire box on the base, three flue sections arranged one on top of the other upon the fire box, the lowermost section having an opening at the center thereof for the reception of gases from the fire box and provided upon opposite sides of said opening with depending fins for dividing and directing to said opening the gases flowing upwardly from said fire box, the intermediate section having openings at substantially diametrically opposite points thereof for the reception of gases from the central opening in the lowermost section and provided over said central opening with depending fins for dividing and directing to the openings in said intermediate section the gases received from the opening in the lowermost section, and the uppermost section having an opening at the center thereof for the reception of gases from the openings in the intermediate section and provided over the openings in the intermediate section with depending fins that divide and direct to the central opening in the uppermost section the gases discharged from the openings in the intermediate section.

2. In a boiler, a flue section having an arched portion extending fore and aft thereof and closed at the rear and open at the front, an elongated opening extending in a line disposed at substantially right angles to the fore and aft line of the arched portion, and two sets of substantially parallel fins depending from the ceiling of the

arched portion in front and in rear of said opening and extending fore and aft of the section in line with and accessible from the open end aforesaid of said arched portion.

5 3. In a boiler, a flue section having an arched portion extending fore and aft thereof and closed at the rear and open at the front, two opposed sets of elongated openings respectively at the front and rear of the arched portion, the openings of each set being in substantially end-to-end relation and longitudinally curved in the arc of a circle, and a set of fins depending from the ceiling of said section intermediate the two sets of openings and extending fore and aft of the section in line with the openings and the open forward end of said arched portion.

10 4. In a boiler, a flue section having an arched portion extending fore and aft thereof and closed at the rear and open at the front, a circular opening at the center of said arched portion, an open ended fluidway of substantially rectangular configuration extending substantially diametrically across said opening, and two sets of fins depending from the ceiling of said arched portion in front and in rear of the opening and extending fore and aft of the section in line with and accessible from the open forward end of said arched portion, and vertically extending fins upon opposite sides of said fluidway and upon opposite walls of said opening.

15 5. In a boiler, a flue section having an arched portion extending fore and aft thereof and closed at the rear and open at the front, an opening at the center of said arched portion, and two sets of substantially parallel fins depending from the ceiling of the arched portion in front and in rear of said opening and extending fore and aft of the section in line with and accessible from the open end aforesaid of the arched portion.

20 6. In a boiler, a flue section having an arched portion extending fore and aft thereof and closed at the rear and open at the front, elongated openings respectively at the front and rear of the arched portion, the openings being longitudinally curved in the arc of a circle, and a set of fins depending from the ceiling of said section intermediate the openings and extending in substantially parallel relation fore and aft of the section in line with the openings and the open forward end of said arched portion.

25 7. In a boiler, a dome section having a vertical opening for the reception of products of combustion, a fluidway extending across said opening at the lower end thereof and having opposite ends thereof opening into the dome section upon opposite sides of the opening, and a passageway for products of combustion projecting laterally from a wall of said opening above said fluidway.

30 8. In a boiler, a dome section having a vertical opening therein for the reception of products of combustion, a fluidway extending across said opening at its lower end and opening into said dome section upon opposite sides of said opening, and a substantially horizontal passageway projecting laterally from a wall of said opening and adapted to receive products of combustion from said opening, the bottom of said passageway being substantially flush with and forming a lateral extension of the top of said fluidway.

35 9. In a boiler, a hollow dome section having an arched portion for the reception of products of combustion extending fore and aft thereof and closed at the rear and open at the front, a vertical opening at the center of said arched portion for the reception of products of combustion,

a fluidway extending across said vertical opening and opening into said dome section upon opposite sides of said vertical opening, and means for directing products of combustion in said arched portion to said vertical opening including substantially parallel fins depending from the ceiling of said arched portion in front and in rear of the vertical opening and extending fore and aft of the section in line with and accessible from the open forward end of said arched portion.

40 10. In a boiler, a hollow dome section having an arched portion for the reception of products of combustion, a vertical opening extending upwardly from the ceiling of the arched portion for the reception of products of combustion, a fluidway extending across said vertical opening adjacent the ceiling of the arched portion and opening into said dome section upon opposite sides of said vertical opening, and means with- in said arched portion for directing products of combustion to said vertical opening.

45 11. In a boiler, a hollow dome section having an arched portion for the reception of products of combustion, a vertical opening extending upwardly from the ceiling of said arched portion for the reception of products of combustion, a fluidway extending across said vertical opening adjacent said ceiling and opening into said dome section upon opposite sides of said vertical open- 50

ing, means for directing products of combustion in said arched portion to said vertical opening including substantially parallel fins depending from the ceiling of said arched portion in front and in rear of the vertical opening, and means for dividing into a plurality of streams the products of combustion received in said vertical opening including vertically extending fins upon opposite sides of said fluidway and upon opposite walls of said vertical opening.

55 12. In a boiler, a hollow dome section having an arched portion for the reception of products of combustion, a vertical opening extending upwardly from the ceiling of said arched portion for the reception of products of combustion, a fluidway extending across said vertical opening adjacent said ceiling and opening into said dome section upon opposite sides of said vertical opening, means for directing products of combustion in said arched portion to said vertical opening including substantially parallel fins depending from the ceiling of said arched portion in front and in rear of the vertical opening, and means within the vertical opening upon opposite sides of the fluidway for dividing into a plurality of streams the products of combustion received in said vertical opening.

60 13. In a boiler, a dome section having an arched portion for the reception of the products of combustion extending fore and aft thereof and closed at the rear and open at the front, a vertical opening at the center of said arched portion adapted to receive products of combustion from said arched portion, a fluidway extending across said opening and opening into the dome portion upon opposite sides of said vertical opening, means for directing products of combustion in said arched portion to said vertical opening including fins depending from the ceiling of said arched portion in front and in rear of the opening and extending fore and aft of the section in line with and accessible from the open forward end of said arched portion, and means upon opposite sides of the fluidway for dividing and directing the products of 70

combustion received in the opening from the arched portion.

14. In a boiler, a dome section having an arched portion for the reception of products of combustion, a vertical opening extending upwardly from the ceiling of said arched portion and adapted to receive products of combustion from said arched portion, a fluidway extending across said opening adjacent said ceiling and

opening into the dome portion upon opposite sides of the vertical opening, means for directing products of combustion in said arched portion to said vertical opening, and means upon opposite sides of the fluidway for dividing and directing gases received in the vertical opening from the arched portion.

JAMES F. MCINTIRE.
